(57) **CLAIM**

The ornamental design for a balloon and rod connector combined with the rod, as shown and described.

DESCRIPTION

FIG. 1 is a perspective view showing my new design with the rod portion removed for a clear disclosure of the end configuration;

FIG. 2 is a reduced scale front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is an enlarged scale perspective view of the cross section along line 8—8 of FIG. 3.
